A. ROTH

AUTOMATIC CIRCUIT BREAKER

Filed March 24, 1926

Inventor:

Arnold Roth,
By Commercial Sheet Metal
Co., Inc.

UNITED STATES PATENT OFFICE.

ARNOLD ROTH, OF BRON, NEAR LYON, FRANCE.

AUTOMATIC CIRCUIT BREAKER.

Application filed March 24, 1926, Serial No. 96,973, and in Germany March 16, 1925.

This invention relates to automatic circuit breakers for electrical apparatus, of the type operated by overloads, particularly short circuit surges.

5 The general object of the invention is the provision of a circuit breaker having a very quick action at the break, accompanied by a quick extinguishment of the arc.

Other objects will be indicated hereinafter 10 or obvious to one skilled in the art upon an understanding of the invention.

In the drawing forming a part of this specification is shown diagrammatically one embodiment of the invention, but the claims 15 are not to be construed as limited to this form alone.

The drawing represents a sectional view 20 of an air-break switch having a magnetic blow-out.

25 In the drawing, *a* represents an arcing horn forming at *a'* one of the break terminals, the other break terminal comprising a cooperating movable member *b* which has connection with the stationary horn member *c*, by a flexible conductor *e*. The terminal *b* has insulated mounting on the movable core member *g* which is pivoted at *d* to the stationary core member *f*. The movable and stationary core members carry respectively

30 the coils *n* and *o* which are connected in series to the line terminal *s*, the other line terminal *t* being connected to the horn *a*. The coils *n* and *o* are wound so that when energized they exert repellent electrodynamic influence on each other tending to 35 swing the movable core portion *g* away from the core portion *f*. A voltage coil *p* is provided on core portion *f*, so proportioned with respect to coils *n* and *o* that under normal

40 current its magnetizing effect is superior to their mutually repellent electrodynamic force, so as to hold core portion *g* in the position illustrated, wherein break terminal *b* is in contact with break terminal *a'*. The

45 horns *a* and *b*—*c* are arranged between the enlarged pole surfaces of a blow-out magnet, the core of which is shown at *m* and one pole surface at *i*, the other being outside the section illustrated. From coil *n* the current

50 flows through a coil *u* on the magnet core, and thence through terminal members *b* and *a'*, thus completing the main circuit of the switch between line terminals *s* and *t*. Coil *p* is energized through the voltage shunt *V*.

55 A catch device *q*—*r* is arranged for engage-

ment upon the outward movement of core portion *g*, to hold the break open.

In operation, the core portion *g* is normally held in the closed position by the magnetizing effect of coil *p*, with terminal *b* in 60 contact with terminal *a'*. Upon the occurrence of an overload current such as on a short-circuit, series coils *u* and *o* are energized by the increased main current to a degree such that their repellent electrodynamic 65 force becomes superior to the magnetizing effect of coil *p*. Thereupon the core portion *g* is quickly swung to the open position, separating terminals *b* and *a'* and opening the circuit. The arc is extinguished by the 70 magnet along the horns *a* and *c*, the magnet being additionally energized by the flow through coil *m*. For a re-setting, the catch *q* must be released from its detent *r*. It will be observed that in the breaking movement 75 the terminal *b* is moved at a greater linear speed than the core portion *g* carrying coil *n*. As a result of the immediate action induced by the mutually repellent coils, and the quick movement of the terminal member *b*, the break is instantaneous and positive, and by the action of the magnet and arcing horns, the arc is quickly extinguished.

80 What I claim is:

1. In a circuit breaker, the combination of 85 a pair of arcing horns, one of said horns having a movable contact portion for conductive engagement with the other horn, a movable core portion carrying the movable contact, a movable coil and a stationary coil arranged to exert mutually repellent effects, 90 said movable coil carried on the movable core member, and means holding the movable contact in closed position against the normal current influence of said coils. 95

2. A circuit breaker comprising relatively 100 movable contact members, coils associated to exert mutually repellent electrodynamic forces upon each other for moving the contact members apart, said coils being energized in the main switch circuit and having mechanical connection with the contact members whereby the separating movement of the contacts is rendered faster than that of the coils. 105

3. A circuit breaker adapted to open on current overload, comprising coils associated to exert mutually repellent electrodynamic forces on each other, a movable member carrying one of said coils, cooperating switch 110

contacts, one of said contacts carried by said movable member, current connections leading the switch current to the movable contact through said coils in series, and means effective to hold the contacts closed while the coils are carrying current of less than the tripping value.

4. A circuit breaker adapted to trip on a predetermined current comprising coils energized by the switch current to exert mutually repellent electrodynamic forces on each other, a movable contact operated by said coils, arcing horns for conductive connection with said movable contact and means holding said contact in electrical connection with both horns against influence of said coils while they are carrying current of less than the tripping value.

5. A circuit breaker for a controlled circuit comprising current coils associated to exert mutually repellent electrodynamic forces on each other, a contact member movable by said coils to open the controlled circuit, arcing horns cooperating with said contact, a blow-out magnet associated with said horns, and connections whereby said coils and magnet are energized by current traversing the contact member.

6. A circuit breaker comprising a pivoted member, a movable contact carried thereby, a contact member cooperating with said movable contact member, current carrying coils associated to exert mutually repellent electrodynamic forces on each other, one of

said coils carried by said pivoted member between its pivot and the movable contact member, and connections through which said coils are energized in series between the line terminals of the circuit breaker.

7. A circuit breaker having, in combination, line terminals, relatively movable contact members operable to open and close a circuit between said line terminals, means normally effective to hold the contact members in closed position, and means to effect relative movement of the contact members to open the circuit between said line terminals, said means comprising coils energized in series in said circuit and associated to exert mutually repellent electrodynamic forces on each other.

8. In a circuit breaker, in combination, relatively movable contact members, line terminals arranged for connection in series by said contact members, coils connected in series between said terminals through said contact members, said coils associated to exert mutually repellent electrodynamic forces on each other, means normally effective to hold the contact members in closed position and operative connections whereby the contacts are separated by the electrodynamic force of the coils upon an overload.

In testimony whereof I have hereunto subscribed my name at Lyon (France) on the 25 day of February A. D. 1926.

ARNOLD ROTH.
